UNITED STATES PATENT OFFICE.

WALTER M. WILLIAMS, OF NEW YORK, N. Y., ASSIGNOR TO WALDES & COMPANY, OF PRAGUE-WRSCHOWITZ, AUSTRIA-HUNGARY, A FIRM COMPOSED OF HEINRICH WALDES, IGNATZ PUC, EDWARD MERZINGER, AND SIGMUND WALDES.

DESIGN FOR A DISPLAY-CASE CARD.

46,013.

Specification for Design. Patented June 23, 1914.

Application filed April 15, 1914. Serial No. 832,133. Term of patent 14 years.

To all whom it may concern:

Be it known that I, WALTER M. WILLIAMS, a citizen of the United States, and a resident of the city, county, and State of New York, have invented a new, original, and ornamental Design for a Display-Case Card, of which the following is a specification, reference being had to the accompanying drawing, forming part hereof, in which the figure is a plan view of a display-case card showing my new design.

I claim:

The ornamental design for a display case card as shown.

WALTER M. WILLIAMS.
